UNITED STATES PATENT OFFICE.

BURT F. UPHAM, OF EVANSTON, ILLINOIS, ASSIGNEE TO SOUTHGATE MACHINERY COMPANY, OF BOSTON, MASSACHUSETTS, A CORPORATION OF MASSACHUSETTS.

FEEDING ATTACHMENT FOR PRINTING-PRESSES.

1,082,374.

Specification of Letters Patent. Patented Dec. 23, 1913.

Application filed November 8, 1910. Serial No. 591,359.

To all whom it may concern:

Be it known that I, BURT F. UPHAM, of Evanston, in the county of Cook and State of Illinois, have invented certain new and 5 useful Improvements in Feeding Attachments for Printing-Presses; and I hereby declare that the following is a full, clear, and exact description thereof, reference being had to the accompanying drawings, 10 which form part of this specification.

This invention is an improvement in automatic sheet feeding apparatus, especially those used in connection with printing presses,—of that class in which the sheets 15 are automatically fed to the point of delivery, or seizure, by the impression cylinder grippers, and which are provided with means whereby if a sheet is not fed in time, or is improperly presented, the feeding 20 mechanism is automatically tripped so as to stop the feed, and the press throw-off-impression mechanism is also usually tripped by the same means—or at the same time—so as to prevent any offset impression from 25 the type upon the packing of the impression cylinder.

The invention is particularly designed for use in connection with the so-called Dexter or Cross feeders, such for example as are 30 illustrated in patents to Cross No. 799,457 of September 12, 1905 and No. 812,260 of February 13, 1906.

The principal object of my invention is to cause the sheet to be withdrawn out of reach 35 of the grippers if it should be misplaced so that no projecting portion of a misplaced sheet will be liable to be caught by the grippers and carried into the press; and in carrying out this invention I utilize part of 40 the sheet feeding devices of the known automatic feeders, such as the Cross feeder,—to produce a quick reverse or backward movement of the improperly fed sheet at the instant that the feeder is tripped.

45 I will now describe the invention as applied to a Cross feeder, and in the description shall refer by numerals to the parts of such feeder as are already in use, and by reference letters to the novel parts which I 50 have applied thereto; but as my invention is a small part of such feeder and practically an attachment thereto, I will only illustrate and describe so much of such a feeder as will enable those familiar therewith to

readily adapt and apply my invention 55 thereto.

While I show the invention as particularly designed for use in connection with the Cross and Dexter feeders I do not wish to be restricted to its use in connection therewith for the invention may be usefully adapted for use in connection with other types of sheet feeding mechanism.

In the drawings—Figure 1 is a side elevation of parts of a printing press and an 65 automatic sheet feeding and tripping mechanism with my invention applied thereto, showing the parts in normal working position. Fig. 2 is a plan view of the parts shown in Fig. 1, partly broken away and 70 partly in section. Fig. 3 is a view similar to Fig. 1 showing the parts in tripped position. Fig. 4 is a view similar to Fig. 1 partly broken away showing the normal operative 75 positions of the parts. Fig. 5 is an enlarged view showing the normal positions of parts when the paper is being fed by rollers 103 and 105. Fig. 6 is a similar view showing the second position of the cam, and means for keeping the roller 105 from contacting 80 with roller 103 when the parts are in normal working operation and the sheet is properly presented. Fig. 7 is a similar view showing the position of the cam when the parts are tripped. Figs. 8 and 9 are detail views of the catch and latch lever. Figs. 10 and 11 are detail views of the devices for locking rolls 98 in raised position. Fig. 12 is an enlarged detail view of the detector and trip actuating devices. Fig. 13 is a reverse view of Fig. 12. Fig. 14 is a vertical sectional view of Fig. 12. Figs. 15 and 16 are enlarged detail sectional views of the comber controlling devices, showing same in different positions. Fig. 17 is a detail plan view of Fig. 16.

In the drawings 1 designates a feed table on which the sheets of paper S are fed forward to the impression cylinder 1^a. Above this table adjacent the feed cylinder is a 100 rocking shaft 5^b; to said shaft 5^b is attached a segment 5^c and on the shaft is a loose arm 5^d, beside the segment 5^c, to which arm 5^d is connected one end of a rod 5^e that is pivotally connected at its forward end 105 to a pivoted lever 49^f which is oscillated by a cam 49^g attached to a driven shaft 49 (see Patent 812,260) by which arm 5^d will be

continuously rocked back and forth. To the arm 5^a is pivoted a pawl 5^a which is provided with a pin 5^v on one side adapted to engage a notch in the upper end of an arm 5^t placed beside segment 5^c and fast on a sleeve 5^u loosely surrounding shaft 5^b. Arm 5^a is normally held against the pin 5^v as by means of a spring 5^w attached to the hub of arm 5^a and to a suitable fixed point. As 10 arm 5^a is oscillated by link 5^t the pawl 5^a is oscillated back and forth above the segment 5^c but is held out of engagement therewith by pin 5^v engaging arm 5^t as the spring 5^w causes arm 5^t to keep in contact with pin 15 5^v and hold pawl raised; and also causes sleeve 5^u to rock with arm 5^a, unless prevented. To the sleeve 5^u is attached depending arms 5^m to which detector fingers 5^m are attached. Said fingers normally rest upon 20 the sheet of paper S fed forward upon the table 1, but if any sheet is not in position to be taken by the cylinder grippers at the proper time the end of the detector fingers 5^m will drop into holes 1^b in the metal plate 25 or strip 1^c on the end of table 1 and will arrest the sleeve and arm 5^a, and prevent the latter arm returning when arm 5^a moves backward and therefore pin 5^v will disengage arm 5^t and pawl 5^a will thereupon drop 30 into engagement with segment 5^c and the latter will thereupon be moved with arm 5^a thereby rocking shaft 5^b thereby causing the trip of the throw-off devices by means of an arm a on shaft 5^b to which is connected 35 a rod 5^a that controls the tripping devices. The pin 5^v will automatically reengage the notch in arm 5^t as arm 5^a rocks.

The shaft 5^b and tripping rod 5^a are kept in normal position and returned to normal 40 position when permitted by means of a spring 5^a strung on the rod between a stop 5^a attached to the frame and collar 5^a on the rod, see Fig. 1.

The sheets of paper S are fed forward in 45 the usual manner by means of the rollers 95 and 98 and 103 and 105 (see Patent 812,260) the shaft of rollers 95 and 103 may be driven by mechanism described in said Patent No. 812,260, so as to feed the 50 sheets forward until just before they reach the point of delivery when the rollers 105 and 98 are lifted from the rollers 95 and 103 and remain lifted until after the sheets are removed by the grippers; but the rollers 55 103 and 95 are given a partial reverse rotation so as to tend to slow down the sheet and prevent it overrunning the point of delivery. The rollers 105 are shown as attached to arms on a rock-shaft 10^a to which 60 is attached an arm 10^b to which is connected a rod 10^c that is normally actuated by a spring 10^d so as to hold rollers 105 in contact with rollers 103. The rear end of rod 10^c engages a lever 9 which is pivoted 65 at 9^a and has a roller 9^b adapted to engage

a cam 9^c on shaft 49, which cam 9^c is provided with a dwell 9^d which when opposite the roller 9^b will permit spring 10^d to lower rollers 103 into engagement with rollers 105 and thus assist in feeding the sheet downward but the cam causes the lifting of the rollers 105 prior to and during the taking of a sheet by the grippers on cylinder 1^b; I have attached to this lever 9 an arm d to which is connected an extension 7^a and to this latter I pivotally attach a latch lever 7^b which is provided with a roller 7^c that is adapted to be engaged by a lug 7^d attached to the side of the cam 9^c at the moment that the grippers would close upon the sheet if properly fed. The outer end of this latch lever 7^b is provided with upper tooth 7^e and a lower tooth 7^f. The upper tooth 7^e is adapted to engage the upper edge 8^a of a slotted guide or catch c attached by a stud 8^b to one arm d of a compound lever pivoted at d' on the frame, which arm d and catch c is normally held in depressed position, Fig. 1, by means of a rod e pivoted to the arm d and having its lower end entered into a guide e^a attached to the frame; and the lower end of rod e is notched as shown at e' and this notch is normally engaged by the pointed end a^b of rod a' which is also entered into the guide e^a at right angles to the rod e. A spring e^c is strung on rod e between the guide e^a and the collar e^d on the rod, spring e^c normally tending to throw the rod e and arm d upward if the rod e^a is released by rod a'. 127

It will be observed that the spring 10^d always tends to move the lever 9 toward cam 9^c and keep roller 9^b in close contact with the periphery of cam 9^c; and this rocking movement of lever 9 tends to pull latch lever 7^b inward; and this movement can occur at any time that the dwell 9^d in the cam comes opposite roller 9^b because at that time the latch lever 7^b is in an intermediate position. 116

In the ordinary construction of the feeder the rolls 105 and rollers 103 are slowed down before the sheet reaches the delivery position and are raised before the rollers 103 are reversed and until the sheet has been taken 115 by the cylinder grippers. Or if a sheet is misplaced and the tripping mechanism operates these rollers 105 will remain raised. In my invention I utilize rollers 105 and 103 to pull back the sheet in case it is misplaced, immediately following the tripping of the feeding mechanism, and for this purpose I provide cam 9^c with a short dwell or recess 9^d which comes opposite the roller 9^b just before the moment that the grippers would 125 ordinarily seize a sheet, and just after the moment that the feeder would be tripped by the detector fingers 5^m if they had been arrested as above described. In such case the rod a' is actuated so as to release rod e 130

whereupon spring e^3 throws rod e and arm d upward and thus prevents the engaging of catch c with the tooth b^5 just at the instant that the notch 9^e comes opposite roller 9^b ; 5 consequently spring 10^d throws lever 9 inward until roller 9^b passes notch 9^e and momentarily lowers rollers 105 into contact with rollers 103 which latter rollers are at that moment being rotated in a reverse direction as above described and consequently 10 the misplaced sheet is momentarily nipped by rollers 103 and 105 and is quickly moved or jerked back, away from feeding position, so that the cylinder grippers will not catch 15 any part of the sheet. This action takes place very rapidly but is most efficient in practice in preventing any part of the misplaced sheet being caught and carried into the press. It sometimes happens that a 20 sheet is damaged or torn at one side on its leading edge so that the detectors 5^m at that point will cause tripping but the other portions of the sheet may be projected sufficiently into the path of the grippers to be 25 caught thereby or a sheet might be slightly misplaced and lie at such an angle that part of it would be caught by the grippers,—but by having the sheet drawn backward away from the feeding position simultaneously 30 with the tripping operation the danger of such sheet being caught by the cylinder grippers, with the resulting annoyance and delay caused by the carriage of a partial sheet into the press is obviated.

In the normal operation of the machine 35 so long as sheets are properly fed to the cylinder, the latch-lever b^2 is locked by tooth b^6 to the tooth c^5 of catch c at the moment dwell 9^e in cam 9^e comes opposite roller 9^b , 40 by reason of lug b^4 which then momentarily engages roller b^3 , (see Fig. 6) and consequently spring 10^d cannot at that moment throw lever 9 outward because the latch lever b^2 then prevents it; although as soon 45 as cam lug b^4 passes roller b^3 , catch lever b^2 drops sufficiently to lower tooth b^5 clear of catch c^5 and leaves lever 9 free to be operated by spring 10^d under control of cam 9^e . But when the parts are tripped by the rocking shaft 5^b as above described, rod a' releases rod e and arm d is thrown upward by rod e , thereby preventing the engaging of catch c with tooth b^5 of the latch lever just in time to permit roller 9^b to enter dwell 9^e 55 in cam 9^e . Consequently although the lug b^4 is then upholding latch-lever b^2 , the latch-lever is not locked to anything, and can be freely moved under the action of the spring 10^d and lever 9 .

The finger i normally rests upon the upper end of a lever 1^x which is fulcrumed on a stud z below shaft d' (see Figs. 15-17); said lever has a roller 1^x on its lower end engaging a cam 49^x on shaft 49 . When the parts 60 are tripped (Fig. 8) arm d rises until fin-

ger i drops into a notch 1^y in the lever 1^x (Fig. 16) and will hold the combers away from the paper while the feeder remains tripped. The lever 1^x when not locked by pin i follows the cams 49^x through suitable connections and raises and lowers the combers in and out of contact with the paper, the combers combing the paper forward when they are held at the lowest point. When the lever 1^x is locked by the fall of pin i the combers are held up as long as the feeder remains tripped and the feeder may be again put into operation by hand lever d^e . All of the foregoing parts are parts of the Cross feeder.

In the interval following the falling of finger i and its catching in notch on lever 1^x (Fig. 16) the sheet is pulled back by rollers 105 and 103 , as already described. After finger i has fallen into notch in lever 1^x (Fig. 16) then arm d rises and the lower lip c^6 of catch c is raised; and as soon as roller 9^b runs out of dwell b^9 ,—thereby giving a slight inward movement to the lever d , and the latch lever b^2 , the tooth b^6 of lever b^2 90 becomes locked with the lip c^6 of catch c and will prevent roller 9^b again engaging the dwell b^9 until the parts have been reset and there is another tripping operation of the shaft 5^b .

To the shaft 100 is connected a lever 6 which is provided with a roller 6^a adapted to engage a cam 6^b on shaft 49 whereby shaft 100 is rocked at the proper times to raise and lower rollers 98 over rollers 95 . In order to lock rollers 98 in raised position so as to prevent feeding of a sheet when the parts are tripped, I provide lever 6 with a pin f , which may be an extension of the pin upon which roller 6^a is journaled. Beside this lever 6 I locate a sliding block g provided with a lug g' adapted to come under the pin f when the parts are tripped and lever 6 raised, and thus hold the rollers 98 elevated. The block g is pressed by a spring g^2 adapted to move it, when permitted, to bring lug g' under pin f , see Fig. 2. The slide g also has a projection g^3 which is adapted to be engaged by a dog d^3 pivoted to an arm d^2 of the compound lever d . 100 When the parts are in working position, Fig. 1, this dog d^3 engages the projection g^3 on the slide g and forces and holds the slide in retracted position, so that the lug g' is out of position to engage pin f and therefore 110 will not interfere with the proper operation of the shaft 100 and rollers 98 .

When the parts are tripped by the actuation of the shaft 5^b , as above described, and rod a' disengages rod e , the lever d is rocked upward by spring e^3 as described, and dog d^3 is moved out of the way of projection g^3 and spring g^2 moves the slide g so as to bring lug g' under pin f .

A lever 8 is pivoted at 8^a below lever d 130

and has a tooth 3^a which is adapted to be engaged by a tooth 6^a on dog 6^a so that when the parts are in working position this lever 8 is freed from the dog 6^a but when the parts are tripped the dog 6^a engages lever 8 and locks the latter. Lever 8 is part of the Cross feeder mechanism and forms no part of the present invention.

The pivot d of the lever d is preferably 30 a rock-shaft, to which said lever d is attached, and on this rock-shaft d is a lever e which is connected a rod e which in turn is connected to the sharp edge 5^a of a weighted lever 5 loosely hung on sleeve 5^b being held by which the weighted end of lever 5 is upheld out of the way of the sheets 6 , when the parts are in working position, but when the parts are tripped and shaft d rotated by the upward throw of lever 8 , so that when lever e drops into the path of the sheet and acts as an additional device to prevent such sheet being accidentally pinched by the grippers. Lever e drops off the rollers 103 and 106 before sheet and locks the sheet from being jammed into the press.

The counterbalanced lever d is provided with a hand piece d^b , and after a tripping operation, when the misplaced sheet has been removed, the operator grasps hand piece d^b and rocks lever d to the position shown in Fig. 1 and holds it and the parts in this position until a sheet has been properly fed down past rollers 25 and 103, and under detector fingers 5^a into gripping position. Thereafter so long as the sheets are properly fed, rod e will be locked by rod z^a , and the parts will remain in operative position.

Operation: As above stated the general operation of the sheet feeding devices is as explained in the Orbes Patents No. 759,457 and No. 819,230, and I refer thereto as more fully explaining and exhibiting one form of feeder to which the invention is especially applicable, and any one familiar with these feeders will readily understand the present invention and its utility in connection with automatic feeders. Assuming that the parts are in the position shown in Fig. 1, then so long as the sheets are properly fed down and into position for seizure by the cylinder-grippers, the detector fingers 5^a will move idly back and forth over the needles, being kept from engaging with any of the holes 1^b by the covering sheet of paper. But if a sheet is misplaced or defective, so that any detector finger 5^a falls a hole 1^b , said detector finger is arrested and stops the application of sleeve 5^b and arm 5^a permits the pawl 5^c to engage pawl 6^a as described, whereupon the rod e is drawn inward and releases rod z^a , which is raised by spring z^b and actuates lever d as described, with the result that the feeding devices are thrown out of operation; and at the same moment the rollers 105 are momentarily

dropped into engagement with rollers 103 and the misplaced sheet is thereby pulled back out of the way, and the weight lever e is dropped upon the withdrawn sheet. The further sheet feeding operations of such feeder are suspended until the defective sheet is removed. Then the operator grasps lever d and returns the parts to the position shown in Fig. 1, and the feeder resumes its operation and continues in operation so long as sheets are properly fed to the cylinder-grippers. In the Cross feeder, the distance between the sheet feeding rollers 95 and the detector finger 7 is such that if a defective or misplaced sheet is removed from the machine, the operator should hold lever d depressed until a sheet has passed under the detector fingers 5^a , so as to prevent a tripping operation occurring before a sheet can be fed down to position for seizure by the cylinder-grippers. Suitable mechanism may be provided as covered in my application filed March 17, 1919, Ser. No. 550,083, whereby when shaft d is rocked this also trips the press.

What I claim is:

1. In automatic paper feeding mechanism, the combination of upper and lower paper feeding rollers, means for rotating the lower rollers alternately in opposite directions, devices adapted to detect a misplaced or defective sheet, and means for raising and lowering the upper rollers, comprising a pivoted lever and a cam; with means for momentarily bringing the upper rollers into contact with the lower rollers when the detector mechanism finds such a sheet, said means comprising a short dwell in the actuating cam for said rollers, and means to prevent said dwell so operating 100 said upper rollers except when the detector mechanism finds a defective sheet, substantially as described.

2. In automatic paper feeding mechanism, a set of paper feeding rollers, means 110 for rotating the lower rollers alternately in opposite directions, an actuating cam, a lever and connections for raising and lowering the upper rollers; devices adapted to detect a misplaced or defective sheet; means 115 for momentarily bringing the said rollers into contact when the detector mechanism finds such a sheet, said means comprising a short dwell in the said actuating cam; with a latch lever connected with the roller actuating lever, a catch for normally engaging said latch lever to prevent operation of said dwell except when the detector mechanism finds a defective sheet, and tripping mechanism controlled by said detecting device whereby said latch lever is released when the tripping mechanism is actuated, substantially as described.

3. In automatic paper feeding mechanism, sets of opposed paper feeding rollers, 130

- devices for detecting a misplaced or defective sheet, means for rotating one set of rollers alternately in opposite directions, means for raising and lowering the opposed 5 set of rollers comprising a cam, a pivoted lever and connections, said cam having a short dwell for momentarily bringing the rollers into contact when the feeding mechanism is tripped; a latch lever connected 10 with the roller-actuating lever, a catch for normally engaging said latch lever to prevent operation of said dwell except when the detector mechanism finds a defective sheet, a tripping rod controlled by the detector mechanism, a rocking lever carrying 15 said catch, a spring actuated rod for vibrating said lever, said tripping rod engaging said spring actuated rod, substantially as described.
- 20 4. In automatic paper feeding mechanism, the combination of a set of paper feeding rollers, means for rotating the lower rollers alternately in opposite directions, means for raising and lowering the upper 25 rollers comprising a pivoted lever and connections, and a cam for operating said lever, and devices adapted to detect a misplaced or defective sheet; a second set of rollers, a cam, a lever engaging said cam for separating the rollers in the second set, and a spring 30 actuated slide adapted to engage said lever to prevent closing of the said rollers when the mechanism is tripped; with means for momentarily bringing the rollers in the first set into contact when the detector 35 mechanism operates, said means comprising a short dwell in the actuating cam for said rollers, a latch lever connected with the roller actuating lever, a catch for normally engaging said latch lever to prevent operation of said dwell except when the detector mechanism finds a defective sheet, and tripping mechanism controlled by the detector mechanism whereby said latch lever is released when the tripping mechanism is actuated. 40
- 45

In testimony that I claim the foregoing as my own, I affix my signature in presence of two witnesses.

BURT F. UPHAM.
